WARREN R. BRIGGS, OF BOSTON, MASSACHUSETTS, ASSIGNOR TO M. G. BRIGGS, OF SAME PLACE.

Letters Patent No. 99,829, dated February 15, 1870.

IMPROVED TABLE-LEAF SUPPORT.

The Schedule referred to in these Letters Patent and making part of the same.

To all to whom these presents shall come:

Be it known that I, WARREN R. BRIGGS, of Boston, of the county of Suffolk, and State of Massachusetts, have made an invention of a new and useful Mode of Sustaining the Folding Leaves of a Table in a Horizontal Position; and do hereby declare the following to be a full, clear, and exact description thereof, reference being had to the accompanying drawings, making part of this specification, and in which—

Figure 1 is an under-side view, and

Figures 2 and 3, transverse sections of a table in which my invention is embodied.

This invention consists in pivoting to the under side of each hinged leaf of a table one or more braces or supports under such an arrangement that upon raising the leaf to a horizontal position, for the purpose of increasing the size of the table, such braces or supports shall be locked automatically to the frame of such table, and with the leaf maintained in this position, the release of the braces and consequently of the fixed position of the leaf being effected by means of a small button or thumb-piece, affixed to one side of the rod upon which the braces are mounted, in manner as hereinafter stated, the purpose of this invention being to effect rapidly and with very little exertion the locking of the leaves of the table in a horizontal position.

In the drawings accompanying this specification, and which illustrate my invention, a table of ordinary manufacture is exhibited at A, the component parts of which are four legs, represented at *a a a a*, and four connecting rails, seen at *b b' b'' b'''*, the center or fixed portion of the top of the table being shown at *c*, and its hinged or folding leaves at *d d*.

In carrying out my present invention I mount upon the under side of each leaf *d* and in suitable bearings or steps *e e* a rod or wire, *f*, while upon such rod I affix one or more curved braces or supports, *g g*, extending inwardly toward the centre of the table and passing through apertures *h* made in each side rail *b''* or *b'''*.

The inner end of each brace is formed with a lip or catch, *i*, to take hold upon the adjacent rail of the table, and the rod *f* should be supplied with a laterally-projecting lip or thumb-piece, *j*, by means of which it may be partially turned in its bearings *e e*.

Upon raising the leaf into a horizontal position, the braces as a matter of necessity follow the movement, and are moved outwardly until the lip or catch *j* of each drops outside of the rail of the table, by this means locking and maintaining the leaf in its proper relationship to the rest of the table.

When it becomes desirable to lower the leaf the thumb or finger is to be applied to the lip *j* and the latter raised, which effects a partial rotation of the rod *f* and raises the free end of the braces to such an extent as to free their catches from contact with the rail of the table and allow the leaf to be lowered, the braces in the act passing inwardly into the space below the center of the table.

I have contemplated inserting a spring between the lip *j* and the top of the table, for the purpose of insuring the proper descent of the braces, but in practice the gravity of the free ends of these braces will undoubtedly be found sufficient to secure the desired result.

The practical utility and value of the foregoing device will at once manifest itself to intelligent people, enabling, as it does, a person to fix the position of the table-leaf without the disagreeable trouble now necessary to effect the result.

Claim.

I claim the construction and arrangement upon the leaf of the table, and in relation to the slots in the table frame, of the rod *f* with its lip *j* and the curved supports *g*, in the manner shown and set forth.

WARREN R. BRIGGS.
